UNITED STATES PATENT OFFICE.

THOMAS SCUDDER, OF GREEN ISLAND, NEW YORK, ASSIGNOR OF TWO-THIRDS TO JOHN H. SCUDDER AND GEORGE T. SCUDDER, BOTH OF SAME PLACE.

WAGON-SEAT FASTENING.

SPECIFICATION forming part of Letters Patent No. 366,692, dated July 19, 1887.

Application filed February 8, 1887. Serial No. 226,886. (No model.)

To all whom it may concern:

Be it known that I, THOMAS SCUDDER, of the village of Green Island, county of Albany, and State of New York, have invented a new and useful Improvement in Wagon-Seat Fastenings, of which the following is a specification.

My invention relates to improvements upon that class of devices which are used to connect a wagon-seat to the body of the vehicle by means of a clamping device; and the object and purpose of my invention are to better adapt such devices by construction to the use for which they are designed.

Accompanying this specification, to form a part of it, there is a plate of drawings containing four figures illustrating my invention, with the same designation of parts by letter-reference used in all of them.

Of these illustrations, Figure 1 is an end elevation of a wagon body and seat with my invention shown applied to connect the seat and body. Fig. 2 is a front elevation of the device shown as detached. Fig. 3 is a central and vertical section of the device, and Fig. 4 is an end elevation of a modification shown as arranged upon one end of the seat and side of the wagon-body.

The several parts of the apparatus thus illustrated are designated by letter-reference, and the function of the parts is described as follows:

The letter B indicates the wagon-body, S the seat, R the body-rail, and C the clamping-hook, which is threaded at t to receive a set-screw nut, N, having finger-pieces f and hook H.

The letter S² designates a sleeve, within which, between its hook end and threaded end, the clamping-hook is placed, and the letters E E designate ears arranged on the side of the said sleeve, adapted to receive screws by which the sleeve is attached to the seat. These ears upon the sleeve are constructed to face parallel with the seat side for attachment thereto;

but the sleeve proper, at its upper end, and also the clamping-hook which it contains, are projected outwardly from the seat side, so as to make an acute angle with the latter, the sleeve proper and the clamping-hook which it contains inclining inwardly toward the seat

end and wagon side as they descend, which angularly-arranged sleeve and clamping-hook place the set-screw so as to be more easily accessible and convenient to operate. This clamping-hook, at its lower end, has arranged thereon a stop, P, projected from its side at right angles to the lateral extension of the hook. This laterally-projecting stop P is formed on the stem of the clamping-hook at a point on the lower part of the stem and near the hook, so as to bring the stop with its inner face against the face of the cleat or rail under which the clamping-hook engages.

The function of the parts thus described is as follows: The apparatus being attached to the seat at the outer or inner side by means of screws inserted in the holes O of the ears E, the lower end of the clamping-hook being passed under the rail R and the set-screw turned, the stop P engages with the side of the rail to prevent the hook from turning as the set-screw, engaging with the upper end of the sleeve, causes the lower end of the clamping-hook to engage with the rail, and thus securely connects the seat and body. Where there is no rail upon the wagon-body, a hook, m, having a strap, v, secured to the wagon side, may be used, and the clamping-hook at its lower end made to engage with said hook m, as shown at Fig. 4.

I am aware that a clamping-hook has before been used for a like purpose, and that such a clamping device has been operated by a cam and also by an arm on the clamping-hook, with a pin on the latter working in an obliquely-arranged cam-slide made in the sleeve which receives the clamping-hook, all of which I disclaim. In the older devices named and disclaimed any sudden vertical vibration of the seat, caused by the vehicle passing over a stone or jog in the road, would jar the parts so as to disconnect them, and this difficulty my device is well adapted to remedy, as the seat and body are securely held together by the set-screw.

Having thus described my invention, what I claim, and desire to secure by Letters Patent, is—

The seat-lock herein described, consisting of the plate E, having side extensions to secure it to the seat, and formed with a hollow

sleeve, S', the bore of which is arranged at an angle inclining from the bottom of the plate outward, a clamping-rod fitted to the bore of the sleeve and formed with clamping end H, a 5 threaded upper end, and lateral extension P, and a setting-nut on the threaded end of the clamping-rod, substantially as described.

Signed at Troy, New York, this 11th day of December, 1886, in the presence of the two witnesses whose names are hereto written.

10

THOMAS SCUDDER.
